UNITED STATES PATENT OFFICE.

CLINTON B. WOODAMAN, OF WORCESTER, MASSACHUSETTS, ASSIGNOR TO EVEREADY MFG. COMPANY OF BOSTON, OF BOSTON, MASSACHUSETTS, A CORPORATION OF MASSACHUSETTS.

STAPLE MAKING AND DRIVING MACHINE.

Application filed March 4, 1920. Serial No. 363,173.

To all whom it may concern:

Be it known that I, CLINTON B. WOODAMAN, a citizen of the United States, and a resident of Worcester, in the county of Worcester and State of Massachusetts, have invented an Improvement in Staple Making and Driving Machines, of which the following description, in connection with the accompanying drawings, is a specification, like characters on the drawings representing like parts.

This invention relates to machines for making and driving staples, and is more especially concerned with a machine of the class in which a plain, flat strip of sheet metal having substantially straight edges is made into staples, which are then driven into sheets of paper, cloth, or other material. The patent to Lea, No. 1,214,930, issued February 6, 1917, discloses an illustrative machine of this class, to which my invention is applicable.

In the machine of the patent, a metallic ribbon, or tape, is drawn from a roll or coil, and is fed to cutting, bending and driving instrumentalities, which cut a piece of the tape, bend it into the form of a staple, and drive the latter. The width of the staple is whatever distance the feed mechanism happens to feed the strip, and this distance in practice is found to vary from time to time, thus producing staples of varying width. My invention aims to impart a uniform feeding movement to the strip, thereby ensuring the production of staples of uniform width.

In the machine of the patent, some inconvenience is experienced in placing a new roll of tape onto the machine, and in threading the tape through the feeding mechanism to the cutting, bending and driving instrumentalities. This inconvenience is due partly to the means of mounting the roll of tape on the machine, and partly to the method of removing the old, remaining piece of tape from the feeding mechanism, and replacing it by the new one. My invention aims to obviate this inconvenience by improving the means for mounting the roll of tape, and by the provision of means to facilitate the removal of the old tape from the feeding mechanism, and its replacement by the new tape.

My invention will be best understood by reference to the following description, when taken in connection with the accompanying drawings of one illustrative embodiment thereof, while its scope will be more particularly pointed out in the appended claims.

In the drawings:

Fig. 1 is a plan of a staple-making and driving machine exemplifying my invention;

Fig. 2 is a side elevation of the same, partly in vertical section;

Fig. 3 is a sectional view on line 3—3 of Fig. 1;

Fig. 4 is a sectional view on line 4—4 of Fig. 1;

Fig. 5 is a sectional view on line 5—5 of Fig. 2;

Fig. 6 is a sectional view on an enlarged scale on line 6—6 of Fig. 1;

Fig. 7 is a detail elevation of a portion of the cutting and bending mechanism, illustrating the operation of bending the prongs; and

Fig. 8 is a detail plan view of a portion of the metal strip illustrating the mode of cutting and forming the prongs of the staple prior to severing and clinching the latter.

Referring to the drawings, and to the embodiment of my invention which I have selected for exemplification, I have shown a staple-making and driving machine comprising a mounting 10 for the supply of sheet material which is herein in the form of a strip 12 of suitable metal, which may be conveniently supplied to the machine in the form of a roll or coil 14. The support may be, and preferably is, in the form of a casing, comprising a body 16 of generally cylindrical form, provided with a slot or aperture 18, through which the free end of the strip 12 may be drawn. The body 16 is herein provided with a central hub or boss 20, to which is secured a cover-plate 22 by suitable means, herein a screw 24, carried by the cover-plate and threaded into said boss. By simply rotating the cover-plate in the proper direction, it may be removed to permit the renewal of the roll of metallic tape when the same has become exhausted.

The strip 12, which emerges from the aperture 18, leads toward the forward end of the machine, where it passes over a suitable

guide and fixed cutter 26 (see Fig. 4), the latter being preferably rounded or beveled, as at 28, to facilitate the introduction of the tape between said guide and an upper guide 30. The latter is herein provided with a shallow groove presenting lateral shoulders 32 to provide the necessary guidance for the strip, and to prevent the same from shifting laterally, while the upper and lower guides 10 30 and 26 hold the strip against vertical displacement. It should here be observed that the lower guide and cutter 26 has its cutting edge 34 positioned obliquely across the path in which the strip is fed. As will 15 appear later, this is of importance in determining the shape of the prongs of the staple. A plate 36 extending obliquely across the path of the strip 12 presents a stop 38, which limits the forward motion of the strip under 20 the influence of the feeding mechanism now to be described.

The strip 12 may be fed intermittently by suitable means, such as a lever 40 (see Figs. 3 and 4) provided with a slot 42, through 25 which the strip is led from the source of supply. Suitable means are provided whereby the feed lever is given a positive, backward, non-feeding movement (during which it travels freely along the strip, and no 30 feeding of the latter takes place), and a non-positive, spring-actuated forward motion. Suitable provision is made, so that if it were not for the presence of the stop, the lever would move the strip a distance greater than 35 the distance from the stop 38 to the cutting plane represented by the cutting edge 34 of the stationary guide and cutter 26. The purpose of this is to enable the strip to be brought up against the stop and urged there- 40 against by resilient pressure during a continued receding motion of means which imparts the positive non-feeding movement to the feed lever, the result being that accuracy of width of the staples is assured.

45 To this end, the lever is herein provided with frictional clutching means, comprising a feed gripper, or dog, 44, in the form of a flat spring secured to the lever, as by a screw 46, and having its lower extremity 50 arranged to engage the upper surface of the strip 12, while the bottom of the slot 42 engages the lower surface of the strip, in such manner that when the lever travels rear- 55 wardly, the spring simply yields and allows the lever to move without occasioning movement of the strip. The latter is at this moment positively locked against rearward movement by reason of the engagement of the previously formed prongs which engage 60 the front face 34 of the lower guide and cutter 26. When the lever is moved in a forward direction, the spring grips the strip against the bottom of the slot, and the strip is carried forward until its forward end 65 brings up against the stop 38.

The feed lever may be actuated by suitable means, herein a rocking cam 48 cooperating with a suitably shaped cam-like surface 50 on the feed lever. During the bending of the staple legs, as hereinbefore described, the cam 48 imparts an idle backward stroke to the feed lever 40 to some such position as that illustrated in dotted lines in Fig. 4. Forward movement of the feed lever takes place under the influence of a suitable spring 52, such movement being normally limited by the forward end of the strip bringing up against the stop 38. When this takes place, the cam 48 recedes from the cam surface 50, leaving a gap therebetween, as illustrated in Figs. 3 and 4, this gap being sufficient to permit a much greater travel of the lever when the feed-dog is disengaged from the strip, as for example, when a new strip is to be inserted in the machine. If the feed-dog is thus disengaged, the feed-lever will continue to move forward under the influence of the spring until finally its movement is limited by a stop pin 54 carried by the lever bringing up against an abutment 56. This feed mechanism ensures uniformity in the width of the staples,—a result which is practically impossible where it is attempted to adjust the stroke of the feed lever to produce a staple 95 of the desired width.

I will now describe the cutting, bending and driving mechanism, whereby the staple is formed from the metallic strip and driven. The strip is first partially severed by two outer cutters 58 and 58' along the lines A and A' (Fig. 8) coincident with the cutting edge 34 of the lower guide and cutter 26, and in a plane oblique to the strip. As these cutters descend and cut the edges of the metallic strip to form sharp pointed prongs, the latter are bent in a downward direction, this being conveniently accomplished by providing the lower ends of the cutters 58 and 58' with rounded or beveled inner corners 60 and 60', substantially at right angles to the oblique plane of the cutting edges before referred to, and imparting to said cutters a stroke considerably in excess of that required simply to slit the metal. In fact, the stroke 110 of the cutters as herein shown is practically equal to the length of the prongs B and B' which they form. It should here be observed that no forming block is required in the space between the prongs thus formed, 115 it being found in practice that the metal can be slit and bent to form a practically right-angle corner by the employment of the cutters, as shown.

The prongs having been formed, the next 120 step is to sever the otherwise completed staple from the strip, and drive the prongs of the staple through the sheet material, after which the prongs are clinched. To this end, I have herein provided a central 130

cutter 62, having its cutting edge disposed in the oblique plane before referred to, which cutter comes into action after the cutters 58 and 58' have completed their work. The cutter 62 descends and completely severs the strip along the line A—A', and practically simultaneously therewith drives the prongs B—B' through the desired sheet material or other article herein represented by C, the prongs being clinched by an appropriate anvil 64 provided with a depression 66 suitably formed to cause the extremities of the prongs to be bent toward each other and clinched, as illustrated in Fig. 6. It is found in practice that the most satisfactory action of the cutter 62 is secured by providing its lower end with a concave formation, as at 68, which gives it a shearing action. It should now be evident that the cutter 62 constitutes also a driving plunger, whose arrangement with respect to the cutters 58 and 58' is such that, by their successive and continuous action in one direction, the staple is completely formed and driven.

In order to produce a staple of the desired width, while still having cutters of the requisite degree of strength, I have herein provided the cutter 62 with a vertical groove 70 (best shown in Figs. 4 and 7), which has sufficient depth (in a horizontal direction from front to back) to receive the stop 38, which limits the forward movement of the strip under the influence of the feeding mechanism. This construction enables me to produce a staple just as narrow as desired, while still providing a sufficient thickness of the cutters to enable them to perform their work without danger of breakage.

As before stated, the cutters are arranged in a plane oblique to the edges of the strip 12, so that the prongs B and B' are formed with angular or sharp points to facilitate their entrance into the material through which they are to be driven, and it should here be observed that, in order to make the prongs B and B' of equal length when they are cut obliquely, the cutters 58 and 58' should be so placed that the line A along which the cutter 58 acts is much longer than the line A' along which the cutter 58' acts. In other words, the effective length of the cutting edge of one cutter, when measured from the adjacent edge of the strip to the bending edge of such cutter, is greater than the effective length of the cutting edge of the second cutter measured from the other edge of the strip to the bending edge of such cutter, though the cutters may be and are herein actually of the same width. In order to illustrate this matter more clearly, I have shown in Fig. 8 dotted lines representing the shape of the forward end of the strip 12 prior to the commencement of

the formation of the staple. It should here be noted that the dotted line D is substantially equal in length to the line A', and that the dotted line D' is substantially equal to the line A. By thus proportioning the slit along the lines A and A', the prongs B and B' in the completed staple are substantially equal in length.

The described cutters may be actuated by any suitable mechanism, whereby they are operated in definitely timed relation, as for example a pair of cams 72 and 72', which actuate the cutters 58 and 58', respectively and a cam 74, which actuates the cutter 62 on the downward stroke. The cam 48, which produces the idle backward stroke of the feed lever 40, is so placed with reference to the cams 72 and 72' which produce the downward movement of the cutting and bending plungers 58 and 58', and with reference to the cam 74, which produces the downward movement of the final severing and driving plunger 62, that the cam 48 engages the feed lever 40 and produces the idle rearward movement of the latter during the bending of the staple legs by the plungers 58 and 58', as will be evident from an inspection of the relative location of the cams in Figs. 3 and 4. This is of importance, as will be evident when it is considered that it requires but one cycle of operation of the machine to feed the strip, bend the prongs, and sever and drive the staple. All of the plungers may be lifted by suitable resilient means, herein a single spring 76, which engages the under side of lugs 78 and 78' on the plungers 58 and 58', and a lug 80 on the plunger 62, and which spring has its terminal portions secured to a suitable support, herein a frame 82 hereinafter described.

As herein shown, the cams just described are secured to a rocking cam shaft 84, to which is also secured a hand lever 86 having a suitable knob 88, which may be struck or pressed in the downward direction by the palm of the hand. As herein shown, this lever is formed integral with the cam 74, and is moreover provided with an integral stop 90 to limit its upward swinging motion, and a similar stop 92 to limit its downward swinging motion. The stop 90 may engage a suitable abutment, herein the rear face of the cutter 62, while the stop 92 engages the front face of the plate 36. The latter also constitutes a means for removably holding the cutters in place, and to that end is perforated to receive a pair of screws 94 and 94', by which it is secured to the frame 82 now to be described.

As a convenient means for supporting the feeding mechanism and the cutting and driving mechanism, I have provided the frame 82 hereinbefore referred to. This frame is bifurcated, as clearly shown in

Figs. 1 and 5, and between its sides, the feed lever 40 is fulcrumed on a pivot 96. The cutter actuating cams are also disposed between the sides of the frame 82, and the latter is provided with suitable bearings for the cam-shaft 84. As a means for normally holding the actuating lever 86 in its elevated position and returning it to such position after it has performed its work, I 10 may employ a spring of any suitable arrangement, such as a spring 98 which is made double, its two free ends resting against bosses 100 on opposite sides of the feed lever 40, and extending thence in an 15 upward and forward direction part way around the hubs of the cams, and thence to the stop 92, the latter being provided with a notch 102 to receive the intermediate portion of the wire of which the spring is 20 formed. Preferably, to give the spring increased resiliency and to prolong its life, the two free ends are bent to form coils 104 intermediate the points of engagement of the spring with the bosses of the feed lever 25 on the one hand and the bosses of the cams on the other.

The frame 82 is herein mounted on a suitable base plate 106, to which it is connected by a pivot 108, whereby it is permitted to 30 rock, and the operator is enabled to insert the sheet material upon the anvil by simply grasping the actuating lever and lifting the latter, which in turn swings the frame 82 in an upward direction to provide 35 the necessary space beneath the cutters and the associated parts, after which the frame may be released and allowed to descend upon the surface of the material. When the latter is appropriately positioned, the operator 40 then presses or strikes in a downward direction on the knob 88, and thus, by a single continuous downward motion, causes the staple to be completely formed, severed from the strip, and applied to the material.

45 The base plate 106 also provides a convenient support for the mounting 10 for the roll of the tape. To enable the mounting 10 to be removed in a rearward direction, that is to say in a direction opposite to the direction of feeding movement of the strip, I have herein provided the mounting and the base plate, one with a socket and the other with a tongue received therein, and separable one from the other by movement of the 50 mounting in the rearward direction. In the present example, the base plate is provided with a socket comprising two pairs of tongues 110, best shown in Fig. 5, struck up from the base plate and overlying a tongue 55 112, herein consisting of a strip of sheet metal having an offset portion suitably secured to the mounting 10, as by a rivet 114. Removal of the mounting 10 is accomplished 60 by simply withdrawing the latter in a rearward direction (toward the right, Fig. 2), 65

and it may be replaced by a reversal of this operation.

In order to facilitate the removal of the old strip and the introduction of a new one, I have herein provided manually-operable means for releasing the feed dog 44 from the strip, said means in the present example comprising a lever 116 (see Fig. 4) received in a vertical slot 118 in the lever 40, and fulcrumed on a pivot 120 passing through both levers. The forward end of the lever 116 engages the rear face of the feed dog 44, while the handle of the lever projects rearwardly to a point where it is conveniently accessible for operation. By simply depressing the handle of the lever 116, the feed dog 44 is sprung forward, and its grip upon the strip 12 is released, thereby allowing the latter to be withdrawn in a rearward direction. In introducing the new strip, the feed dog may be similarly sprung forward to facilitate the passage of the strip on its way to the cutting, bending and driving instrumentalities.

Having thus described one embodiment of my invention, but without limiting myself thereto, what I claim and desire by Letters Patent to secure is:

1. In a machine for handling strip material, the combination of a mounting for a coil of the material, means for feeding the material from the coil, a base for said mounting and said feeding means, and means providing for the attachment of said mounting to and its detachment from said base by movement of said mounting in the same general direction as the path of the feeding movement of the material.

2. In a machine for handling strip material the combination of a mounting for a coil of the material, means for feeding the material from the coil, a base for said mounting and said feeding means, and means providing for the attachment of said mounting to and its detachment from said base by movement of said mounting in a direction generally parallel with the path of the feeding movement of the material.

3. In a machine for handling strip material, the combination of a mounting for a coil of the material, means for feeding the material from the coil, means for releasing the material from said feeding means thereby to allow the material to be withdrawn in a direction opposite to the direction of feed, a base for said mounting and said feeding means, and means providing for the detachment of said mounting from said base in the first-mentioned direction.

4. In a machine for handling strip material, the combination of a mounting for the coil of material, means for feeding the material from the coil, means for releasing the material from said feeding means thereby to allow the material to be withdrawn in a di-

rection opposite to the direction of feed, and a base for said mounting and feeding means, said base and said mounting being provided, one with a guide and the other with a slide 5 guided therein in the same general direction as the path of feed.

5. In a machine for handling strip material, the combination of a mounting for the coil of material, means for feeding the 10 material from the coil, means for releasing the material from said feeding means thereby to allow the material to be withdrawn in a direction opposite to the direction of feed, and a base for said mounting and feeding 15 means, said base and said mounting being provided, one with a socket and the other with a part received in said socket and detachable therefrom in a direction generally opposite to the direction of the feed.

20 6. In a machine for handling strip material, the combination of a mounting for the coil of material, means for feeding the material from the coil, means for releasing the material from said feeding means thereby to allow the material to be withdrawn in a direction opposite to the direction of feed, and a base for said mounting and feeding 25 means, said base being provided with a socket and said mounting being provided 30 with a tongue received in said socket and removable therefrom in a direction generally opposite to the direction of said feed.

7. In a machine for handling strip material, the combination of mechanism for 35 imparting a step by step movement to the strip by alternately gripping and releasing the strip, said mechanism comprising a reciprocating element having an aperture to pass the strip, a resiliently pressed member 40 on the face of said element having a center of movement away from the same remote from the aperture and an end presented adjacent the aperture and a cam lever pivoted to the element and having a portion to engage 45 said member to release the gripping engagement thereof with the strip.

8. In combination with a framework comprising lateral arms 82, means for feeding a strip forward between said arms comprising 50 an intermittent grip device housed between them and including a pair of cooperating gripping members and a lever projecting from said arms for ready manual operation

to separate said members and release them from the strip.

9. In a machine for feeding and cutting strip material, the combination of feeding means including a reciprocating gripper which alternately grips and releases the material to impart a step-by-step longitudinal 60 feeding movement to the strip, a stop against which the forward end of the strip is brought at each feeding step, and cutting means interposed between said feeding means and said stop and adapted to cut successive pieces from said strip at each advance, said feeding means having capacity for resilient feeding movement greater than the distance from said stop to the cutting 65 plane.

10. In a machine for feeding and cutting strip material, the combination of feeding means including a reciprocating gripper which alternately grips and releases the material to impart a step-by-step longitudinal 70 feeding movement to the strip, a stop against which the forward end of the strip is brought at each feeding step, and cutting means interposed between said feeding means and said stop and adapted to cut successive pieces from said strip at each advance, said feeding means having capacity 75 for resilient feeding movement greater than the distance from said stop to the cutting plane, and having provision to urge said 80 strip with spring pressure against said stop.

11. In a machine for feeding and cutting strip material, the combination of feeding means including a reciprocating gripper which alternately grips and releases the material to impart a step-by-step longitudinal 90 feeding movement to the strip, a stop against which the forward end of the strip is brought at each feeding step, cutting means interposed between said feeding 95 means and said stop and adapted to cut successive pieces from said strip at each advance, said feeding means having capacity for resilient feeding movement greater than the distance from said stop to the cutting 100 plane, and a final limiting stop to limit the movement of said feeding means when the latter is freed from the strip.

In testimony whereof, I have signed my name to this specification.

CLINTON B. WOODAMAN.
